UNITED STATES PATENT OFFICE.

FRED A. CONRAD, OF MILWAUKEE, WISCONSIN, ASSIGNOR TO AMERICAN LACE PAPER COMPANY, OF MILWAUKEE, WISCONSIN, A CORPORATION OF WISCONSIN.

DESIGN FOR A PAPER NAPKIN.

Application filed April 23, 1928. Serial No. 26,434. Term of patent 14 years.

To all whom it may concern:

Be it known that I, FRED A. CONRAD, a citizen of the United States, residing at Milwaukee, in the county of Milwaukee and State of Wisconsin, have invented a new, original, and ornamental Design for Paper Napkins, of which the following is a specification, reference being had to the accompanying drawings, forming part thereof.

In the drawings:

Figure 1 shows a fragmentary plan view of the corner of a napkin embodying my design, the major portion thereof being illustrated diagrammatically and the portion adjacent a border intersection being illustrated in full.

Figure 2 is a section taken in the plane indicated at 2—2 in Figure 1.

Like parts are identified by the same reference characters in both views.

It will be understood that the three corners of the napkin which are not illustrated in the drawing correspond in design to that corner which is illustrated.

In the border the blocks 5, 6, 7, 8, 9 and 10 of general rectangular contour, are higher than areas 11, 12, 13, 14 and 15 in the plane of the napkin.

The entire surface of the napkin is provided with fine ribs disposed at different angles in adjacent areas as shown at 16, 17, 18, 19, 20, 21 and 22.

I claim:

The ornamental design for a paper napkin substantially as shown and described.

FRED A. CONRAD.
